INVENTOR:
Evelyn H. Owen

UNITED STATES PATENT OFFICE.

EVELYN HUGH OWEN, OF LONDON, ENGLAND.

INTERNAL-COMBUSTION ENGINE.

Application filed May 13, 1922. Serial No. 560,855.

To all whom it may concern:

Be it known that I, EVELYN HUGH OWEN, a subject of the King of Great Britain, residing at 6 Comeragh Road, London, in the 5 county of Middlesex, England, have invented a new and useful Internal-Combustion Engine (for which I have filed application in Great Britain, No. 1924, on Jan. 13, 1921), of which the following is a specification.

10 This invention relates to a working process in and means for the construction and operation of an internal combustion engine, the object being particularly to afford augmented pressure so that sustained or increased power-output may be produced whenever load-increase requires it, and to render the working effort or torque more flexible and controllable than heretofore. For such purpose it is necessary to obtain 20 at will suitably augmented mean effective cylinder pressure. Consequently the power impulses or combustion-expansion pressures require to be capable of being varied in magnitude, which effect necessitates adequate variation of the admission volumes and regulation or control of the compression pressure. Accordingly the nature of the improved working process will first be described.

The present invention includes practical 30 characteristics which I term, firstly, compound or dual induction, affording augmented or variable admission of combustible and/or air therefor, and, secondly, pressure regulation, furnishing compression or combustion capacity varied or variable in proportion to such variable admission.

A four-stroke cycle of operations may be worked at will so as to permit the following conditions: simple induction, i. e., by 40 the admission strokes of the power piston alone, or compound induction, i. e., pump-fed variable charges added to the charge drawn into the combustion cylinder, the compression capacity of which is adjusted. 45 When the cycle is being worked with pump-fed induction and adjustable compression the combustion-cylinder piston may draw in either a gaseous or an air charge, a device by means of which this feature may be effected being described hereinafter.

In a two-stroke cycle the working process likewise permits operation of the ordinary induction for cylinder charging, the cycle being performed when required either with 55 the addition of variable pump-feed and ad-

justable compression-clearance or entirely, i. e., constantly, by the said pump-feed and compression-adjustment.

It is thus possible to obtain the equivalent effect of increasing not only the power-cylinder diameter but also the travel of its piston at admission to any practicable extent coincident with which the piston clearance for the compression is proportionately increased. The process is applicable to, e. g., 60 high or slow speed, single or double acting reciprocating piston engines, and opposed, or double piston, action. In the latter case one of each pistons in each power cylinder may function as a compression pressure regulator 65 in the manner described hereinafter with reference to Figure 4.

A preliminary brief description of the accompanying figures, which are purely diagrammatic, is as follows: Fig. 1 represents 70 the path described by the crankpin of a working piston on a four and a two stroke cycle, together with various positions assumed by a pumping piston, when the latter is caused to operate during such cycles. Fig. 2 is an end-elevation view of a single acting 75 four-stroke cycle engine having movable secondary pistons in the heads of each of its four working cylinders and an adjacent single acting auxiliary feed-pump. Fig. 3 is an 80 end-elevation view of a single acting two-stroke cycle engine having similar secondary pistons in the heads of each of its two working cylinders and an auxiliary double acting feed-pump. Fig. 4 is an end-elevation view 85 of an engine having in each working cylinder two opposed pistons, one of which is adjustable in stroke, adjacent to the working cylinders being the aforesaid auxiliary pump. In all of these views the pump is 90 shown variable in travel from no motion to full stroke. Movement of the secondary compression-space varying piston, shown in Figs. 2 and 3, is controlled by that of the curved guide likewise shown in those views, 95 the commencing point of the stroke of the upper piston illustrated in Fig. 4 also being varied by different inclinations of the guide shown in that figure. Figs. 5, 6, and 7 are 100 various views shewing examples of alternative means whereby, in lieu of the aforesaid secondary and opposed pistons, the compression-capacity of the working cylinders may be adjusted. Fig. 8 is a plan view of the engine shown at Fig. 2, illustrating some posi- 105

110

tions in which the said pump may conveniently be placed.

The existing four-stroke cycle of operations is represented approximately by the diagram, Fig. 1. At its initial admission outstroke the crankpin passes through the semi-circle A—B. At or about B the compression stroke is performed with the crankpin passing through the arc B—C. The firing and exhaust strokes occur while the crank describes the arcs D—E and E—F respectively.

The operation of the process in its relation to the foregoing four-stroke system of operations is shown with reference to the same diagram (Fig. 1). As before, on the admission stroke the crankpin describes the semi-circle A—B, but at or about the point 1 a piston reciprocated within a pump cylinder adjacent to the power cylinders commences to draw in an additional charge of combustible mixture and/or air. At or about the point 2 the admission stroke of the pump ceases. The return stroke of the pump piston expels the additional charge-volume from its own cylinder, discharging it into the power cylinder while the crankpin describes approximately the quarter-circle 2—3 on its compression stroke. At or about the point 3, all external communication with the power cylinder being cut off, compression of the combined volumes commences and continues until the crank reaches to about the point 4, when ignition (or fuel-injection), combustion and expansion occur between D—E, and exhaust between E—F.

To compensate for the variable charge-volumes compressed, as described, between the points 3—4, the compression-combustion space in each power, or working, cylinder is enlarged or reduced automatically and progressively in proportion to such charge-volumes.

The operation of the process in its relation to the two-stroke cycle is also shown diagrammatically with reference to Fig. 1. At or about the point 5 on the crank circle DEF, a firing stroke having begun in the first power cylinder, at about 7 a compression stroke has commenced in the second power cylinder. While the first power piston passes between 5—6, the aforesaid pump-piston, having double action inducing a gaseous charge (or air therefor) at each downstroke and an air charge at each upstroke, makes an upstroke discharging a combustion volume (already induced by its previous down-stroke) into the second power cylinder while the piston therein passes between 7—8. Between 6—7 the first power piston opens and closes its exhaust port during which period the pump piston makes its return downstroke discharging scavenging air (already induced by its previous upstroke) into the first power cylinder. The

next succeeding upstroke of the pump discharges a combustion volume (already induced by its previous downstroke) into the first power cylinder while the piston therein passes between 7—8. All external communication with the power cylinder being cut off at or about the point 8 compression by the power piston of the combined charges continues until the inner dead centre is reached, fuel-injection and/or combustion and expansion occurring while the crankpin describes approximately the arc D—E. With reference to the foregoing description it is to be understood that the pump piston is single-acting to feed four single-acting or two double-acting four-stroke power cylinders, and is double-acting to feed two single-acting two-stroke power cylinders. It is further to be understood that the induction stroke of the pump piston is timed or set to suit the relative position of the power piston and valve setting respectively.

The manner whereby the objects mentioned are attained is illustrated in the accompanying diagrammatic drawing in which

Figure 2 is a vertical end elevation of a four-stroke four-cylinder engine; Fig. 3, a similar view of a two-stroke two-cylinder engine; Fig. 4, a similar view of an engine showing double-piston action; Figs. 5, 6, 90 95 and 7 being views of compression-clearance adjustment mechanism. Fig. 8 is a plan view of the Fig. 2. Similar numerals refer to similar parts throughout the views.

The application of this invention will now be described by way of example with reference to a single-acting, four-stroke, four cylinder reciprocating engine. Referring to Fig. 2, the mechanism comprises essentially a piston 1 having a stroke variable from zero to maximum travel reciprocated within a cylinder 2 in valvular or like communication 3 with each power cylinder (one of which is shown at 4 having a valve chest at 4^A), a combustible mixture and/or air supply pipe 5 also being in valvular or like communication with the cylinder 2. The maximum capacity of the cylinder 2 (termed the pump cylinder) is according to the proportion required to that of the power cylinder 115 (4) and to the cycle of operations.

The pump piston 1 is coupled to a connecting rod 6, which in turn is coupled to a link 7 that is reciprocated by or through the main crankshaft, e. g., the link 7 is 120 coupled to the crank 8 turned by the pinion 9 geared at a velocity-ratio of 2:1 to the wheel 10 rotated by the crank 11 connected by the rod 12 with the power piston 13. The piston 1 is set to reciprocate at any suitable time or speed in relation to that of the power piston 13, i. e., when the latter is at half-stroke the piston 1 is commencing its outstroke. In order that the piston 1 may be controlled manually and/or auto- 130

matically by, e. g., a governing device, the big-end of its rod 6, or one end of the link 7, is arranged with a suitable slipper 14 so as to slide on a curved guide 15, which is mounted or pivoted, e. g., centrally as at 16, or eccentrically, that it may be adjusted to various inclinations. The movement of the guide 15 is in control of or connected with the mechanism for varying the clearance 5 in the power cylinder. Thus, at one end, as 10 of the guide 15 is pivoted a rod 18 coupled to a crank 19 on the shaft of a toothed wheel 20, which wheel meshes with the wheel 21 mounted on the end of the shaft 15 15 22, the upper end of which shaft is provided with a worm 23 engaging with a wormwheel 24. On the shaft of the wormwheel 24 is an eccentric or cam 25 in contact with the piston 26 within the cylinder-crown extension 20 27.

When the guide 15 is moved about its pivot 16 the rod 18 is likewise moved together with the crank 19 and consequently the wheels 20 and 21 rotate, through the 25 spindle 22, the worm 23 and the wormwheel 24, thereby causing the cam 25 to raise or lower the piston 26 in the cylinder 27. This, a form of the compression or pressure regulator already referred to, increases or 30 reduces the clearance behind the power piston 13. Full stroke of the piston 1 is obtained when the guide 15 is moved on the pivot 16 towards the vertical and a gradually decreasing stroke to no motion when the 35 guide is moved to a horizontal position in which the link 7 will swing the slipper 14, and consequently the lower end of the rod 6, to and fro, intermediate stroke-lengths being obtained at intermediate positions of 40 the guide.

The application of this invention to the two-stroke cycle is shown with reference to the view, Fig. 3, of a two-cylinder single-acting engine. It will be seen that the feed-pump and compression-clearance adjustment mechanism is identical with that relating to the fourstroke cycle, the rod 6, coupled to a piston rod, being of suitable length to correspond with the radius of the curve of the 45 guide 15. All the parts numbered 1 to 27 operate in the manner already described. The pump cylinder (2), closed at both ends for double action and arranged for its piston to draw in a gaseous charge (or air 50 therefor) at each downstroke and an air charge at each upstroke, is provided with an air intake port A and an outlet pipe A¹ to the valve chest 4¹ in the cylinder 4, each combustion cylinder (as 4) being furnished 55 with an exhaust port B. The approximate relative positions of the pump piston (1) and one of the power pistons (as 13) are as shown in the diagram (Fig. 3).

The invention applied to an engine of the 60 double piston type is shown with reference

to the view, Fig. 4. In this form the function of compression clearance adjustment is performed, as already mentioned, by one of the constantly moving pistons in each combustion cylinder instead of by intermittently 70 movable pistons (as 26, Figs. 2 and 3). All the parts numbered 1 to 19 operate as prescribed with reference to Figs. 2 and 3. The upper piston 13^A is coupled by the pin 21^a to the rod 22, which is coupled by the pin 23^a 75 to the link 24^a and lever 25^a. The link 24^a is coupled to the crank-pin opposite to that of the rod 12, and the lever 25^a is journalled at 26^a on a gearwheel, disc or the like 20 mounted suitably on a horizontal shaft to 80 which the crank 19 is also suitably connected. As the pin 26^a is shifted downwardly the piston 13^A makes its strokes closer to the top point of the piston 13; as the pin 26^a is shifted upwardly the strokes of the piston 85 13^A are made at distances correspondingly further from the top point of the piston 13. In this manner the compression clearance between the two pistons (13 and 13^A) is increased or reduced, and, as the rod 18 and 90 crank 19 are connected to the axle of the part 20 on which is the pin 26^a, upward and downward movement of the point 17 on the guide 15 corresponds with the shortening and lengthening respectively of the stroke 95 of piston 13^A.

With regard to the operation of the four-stroke cycle with feed pump admission supplementing an air charge drawn into the working cylinders, this may be effected by 100 arranging, for example, a three-way cock in the main intake pipe to the power cylinders, so that the normal gaseous charge is thereby cut off at will and communication opened instead with a pure air supply. In 105 this manner the power pistons will then induce plain air, the pump alone feeding the power cylinders with combustible mixture.

It is further to be observed that various combinations or modifications are fairly 110 within the scope of the present invention. For example, referring to Fig. 3, it will be seen that by connecting both ends of the pump cylinder (2) with a combustible supply pipe common to both the pump piston 115 may feed a double charge to four four-stroke combustion cylinders. Referring, now, to Fig. 1, since by this process on a two-stroke cycle a working cylinder receives a pump charge between the points 6—7 and 7—8, it 120 follows that, if on a four-stroke cycle, the main intake valve be arranged to cut off at the point 6, the working cylinder can likewise receive two pump charges delivered between the said points.

The position of the pump cylinder in relation to that of the power cylinders is indicated by the diagrammatic plan view, Fig. 8, in which the pump cylinder 2 is laterally adjacent to the power cylinders 4, 130

4^m, 4ⁿ, 4°. Alternative positions for the pump cylinder are shown at 2^a and 2^b respectively.

Alternatives to the movable piston pressure regulator (as 26, Figs. 2 and 3) are shown by way of example with reference to the Figs. 5 to 7. In Fig. 5 the working cylinder head 4 is provided with a disc or piston *p* having at *r* a rack in mesh with a pinion *g*. As the pinion *g* is rotated so is the disc *p* caused to rise or fall in the compression space above the power piston. In Fig. 6, the part *p*, described with reference to Fig. 5, is replaced by a sleeve or trunk *s*, closed at its top by the crown *si*, having within it the working piston 13, and extending downwardly below the mouth of the working cylinder 4 within which it is telescoped by means of a rack or the like *r* meshing with a pinion *g*. The sleeve *s* has a port *s*² so as to permit free constant communication between the valve chest 4^a and the interior of the cylinder 4. The telescopic motion communicated to the parts *p* and *s* (Figs. 5 and 6) is similar to that of the part 26 (Figs. 2 and 3) and in similar manner thereto the axle of the pinion *g*, (Figs. 5 and 6) is suitably connected by, e.g., the rod 18 and crank 19 (Figs. 2 and 3) to the pin 17 of the guide 15, adjustment of the latter consequently causing variable or varied compression clearance in the working cylinder (4). In Fig. 7 the working cylinder head 4 is arranged with a series of blind or closed-end ports *c*¹, *c*², *c*³ cut off by the mushroom valves *c*⁴, *c*⁵, *c*⁶ and opened to the compression space progressively by depression of the rod 1 pivoted at or about *f*.

The valve mechanism of the pump and power cylinders may be of any suitable known kind and is arranged suitably to permit appropriate admission, cut-off and distribution. A single intake valve may be used in the combustion cylinder. By means of any suitable device, such as a slidable camshaft having cams of appropriate profile, the main cylinder inlet valves may be delayed in closing to correspond with the end of the pump discharge strokes, a non-return valve trapping the normal charge already induced.

I wish it to be understood that by constructing the said pump for multiple action it will feed several power cylinders. For example, if double-acting it may supply supplementary charges to as many as eight four-stroke single-acting power cylinders.

The invention is described and illustrated by way of example only.

60. What I claim and desire to secure by Letters Patent of the United States is:

1. In an internal combustion engine, a power cylinder having a piston chamber, a piston adapted to reciprocate therein, a crank shaft connected to said piston, means

for supplying an explosive charge to said cylinder, a pump cylinder arranged adjacent said power cylinder, a piston mounted therein, a connecting rod connected thereto, a link operatively connected to the crank shaft to be reciprocated thereby, said link being connected to said connecting rod, means for guiding the connected end of said rod and link through a desired path, means for changing said path to vary the travel of the piston in the pump cylinder, and means controlled thereby to vary the combustion space in the power cylinder.

2. In an internal combustion engine, a power cylinder having a combustion chamber, a movable head mounted in said cylinder to permit variation of the size of said combustion chamber, an eccentric connected to said head to control its position, a reciprocating piston mounted in said cylinder, a crank shaft operatively connected thereto, means for supplying an explosive charge to said cylinder, a pump cylinder arranged adjacent said power cylinder, a piston mounted therein, a connecting rod secured to said piston, a link operatively connected to said crank shaft to be actuated thereby, the other end of said link being connected to said connecting rod, means for guiding the connected ends of said rod and link through a desired path, means for changing said path to vary the throw of the piston in the pump cylinder, and means controlled thereby to actuate said eccentric to vary the position of said movable head.

3. In an internal combustion engine, a power cylinder having a combustion chamber, a piston adapted to reciprocate in said cylinder, means for supplying an explosive charge to said cylinder, a pump cylinder arranged adjacent said power cylinder, a piston mounted therein, a connecting rod secured to said piston, a link operatively connected to said crank shaft to be actuated thereby, the end of said link being secured to said connecting rod, a curved guide pivotally mounted adjacent said connection, the ends of said connecting rod and link being mounted in said guide to move therein, a link connected to one end of said guide, a shaft connected to said link to be revolved by the movement of said link, gearing connected to said shaft, and means controlled by the actuation of said gearing for varying the size of the combustion chamber in said power cylinder.

4. In an internal combustion engine, a power cylinder having a combustion chamber, a movable head mounted in said combustion chamber to permit variation in the size of said chamber, an eccentric connected to said head to control its position, a piston mounted in said cylinder, a crank shaft operatively connected to said piston, means for supplying an explosive charge to said

cylinder, a pump cylinder arranged adjacent said power cylinder, a piston mounted therein, a connecting rod secured to said piston, a link operatively connected to said crank shaft to be actuated thereby, the ends of said link being connected to said connecting rod, a curved guide arranged adjacent the connected ends of said link and

10
said connecting rod, a member arranged in said guide and secured to said connection, a link connected to the other end of said guide, a shaft adapted to be rotated by the movement of said second link, and gearing connecting said shaft and said eccentric.

EVELYN HUGH OWEN.
